HARRY BRAMMER, OF BURLEY, LEEDS, ENGLAND.

CYCLE AND LIKE BELL.

1,035,681.

Specification of Letters Patent. Patented Aug. 13, 1912.

Application filed September 8, 1910. Serial No. 581,051.

To all whom it may concern:

Be it known that I, HARRY BRAMMER, of 20 Greenhow Place, Burley, Leeds, in the county of York, England, have invented new 5 and useful Improvements in Cycle and Like Bells, of which the following is a specification.

This invention relates to improvements in cycle and like bells. Hitherto in this class 10 of bell the gong or dome has either been made stationary, or to rotate, and the sounding mechanism when actuated by the trigger is first moved in one direction, and when it,—the trigger,—is returned to its normal 15 position the direction of the actuating mechanism is reversed.

The object of this invention is to utilize 20 the free wheel principle and apply it to cycle and like bells and to achieve this purpose by providing means whereby a continuous rotary motion of the disk carrying 25 strikers is obtained, and which is not affected by the reversal of the movement of the actuating trigger.

25 In the drawings hereunto annexed is illustrated mechanism for achieving this object, in which—

Figure 1. is a sectional elevation of a bell 30 provided with two gongs; Fig. 2. a plan of the same looking at the top with the upper gong removed; Fig. 3. is a part elevation of one disk striker and actuating mechanism adapted for applying the invention to bells 35 of ordinary construction; Fig. 4. is an elevation of a pair of disks and actuating mechanism constructed in a slightly modified form; Fig. 5. is a sectional elevation of a 40 disk and strikers with means for holding the strikers in position; Fig. 6. is a plan of same.

Like parts in all the views are marked with similar letters of reference.

a, a, are a pair of gongs or domes of the usual and ordinary construction, and of the 45 same or different tones, provided with internal projections or striking pieces b, b. If desired the striking pieces b may be formed out of the perimeter of the bell, as shown in the drawings, or they may take the form 50 of internal projections which are cast therein and extend for any suitable distance. The domes a are fixed by screws c to the arch or bridge portion d of the central framework e which is in ring form and provided 55 with the internal projections f, g, upon which a portion of the sound actuating

mechanism is fixed. The arches d may be made integrally with the central frame e, or they may, as shown in the drawings, be secured thereto. Each arch is provided with 60 a boss or bearing h into and through which the screw c is passed, and in the ends of the screws are formed V-shaped bearings for the central spindle i which is made to revolve freely between the arches. 65

On the spindle i are mounted and fixed two disks j, k at suitable distances apart. Each disk is provided with a number,—say, two,—strikers l arranged to reciprocate freely upon pins m which may either be riveted or otherwise fixed to the disks, as 70 shown at Fig. 1, or the pins m may each be fixed to one end of a flat spring n which springs are secured at their other ends to one of the faces of the disks j and k, as 75 shown at Figs. 5 and 6. The pins m pass through the strikers l and into holes in the disks formed to receive them. The central holes in the strikers l are made larger in size than the diameter of the pins m in order 80 that during the rotation of the disks the strikers may be thrown outward for coming in contact with the internal projections b on the gong a.

On the spindle i is mounted loosely between the disks a spur pinion o and an annular sleeve p. On the spur pinion o are provided inclined projections q arranged to mesh with corresponding inclined recesses r formed in the upper edge of the annular 90 sleeve q. In the lower edge of the said annular sleeve are also formed a second set of inclined teeth s smaller in size than the inclined projections q and also inclined in an opposite direction. The inclined teeth s are 95 arranged to mesh with the inclined teeth t formed on or attached to one of the surfaces of a boss 7 which may either form part of the disk k or be separately fixed to the spindle i. 100

The spur pinion o is made to engage with a spur wheel u which is narrower in width than the spur pinion o. Fixed to the spur wheel u is a second spur pinion v with which the tooth segment w and the trigger or operating device x,—provided with the enlarged thumb piece y,—is made to mesh. The spur wheel u and pinion v are mounted upon pin z which is fixed to the internal projection f and the operating lever x is pivoted to a pin 1 which is carried by the internal projection g. 105 110

In the modified form of apparatus shown at Fig. 4. two spur pinions o and 2 are mounted and fixed upon the central spindle i between the disks and the said spur wheels 5 are made to gear with two separate spur wheels u and 3 of narrower width mounted upon a long spindle 4 which is employed in place of the one marked z , shown at Fig. 1, and in this case a spur wheel 5 takes the place of the spur pinion v , and the spur wheel is provided with the inclined teeth q , and the spur wheel u with the inclined projections t , and the annular sleeve p is then mounted upon the pin 4 instead of upon the central spindle i . In this instance the tooth segment w of the trigger x is made to gear with the spur wheel 5 . In all other respects the apparatus is the same as that described for Figs. 1 and 2.

20 At Fig. 3. is shown a method for applying this invention to the existing type of bell where only one disk j is employed, then a tube 6 is fixed to the disk by any suitable means and the boss 7 provided with the inclined teeth t on its upper edge is then made separate from the disk k shown at Fig. 1. In this case the spur pinion o , and the annular sleeve p are mounted loosely upon the sleeve 6 , and the boss 7 is fixed upon the sleeve 6 . In all other respects the apparatus is the same as that shown at Fig. 1.

The action of the mechanism shown at Figs. 1 and 2 is as follows:—The trigger x by means of its tooth segment w actuates the spur pinion v and motion is transmitted through wheel u to spur wheel o , on the underside of which are the inclined teeth or projections r . As the wheel o rotates by the inclined teeth coming in contact with the inclined teeth t on the upper edge of the sleeve p the wheel o is moved up the central spindle i and jams or wedges the annular sleeve by moving it downward so that the inclined teeth s and t come in contact with the boss 7 thereby imparting a rotary motion to the central spindle i and disks j and k mounted thereon which causes the said disks to rotate in the same direction as the central spindle i when the trigger x is returned to its normal position and therefore moved in an opposite direction by pinion o and annular sleeve p being mounted loosely upon the central spindle i . As the action of the trigger is reversed the inclines on the upper portion of the annular sleeve and the inclined projections will then be allowed to return to their normal position, and in so doing the smaller teeth s at the bottom of the sleeve p will be enabled to ride over the teeth t and thus permit of the disks continuing to revolve in their original direction independently of the movement of the trigger x and tooth segment w . As the disks j and k revolve the strikers l are thrown outward and come in contact with the projections b whereby the

gongs are sounded for giving the necessary alarm.

At Fig. 4. the motion is imparted from the trigger and tooth segment w to wheel 5 and the action is thus the same as that already described.

For Fig. 3. the same action is employed as at Fig. 1; the spur wheel o gearing with spur wheel and pinions marked respectively u and v and operated as described by the trigger and its tooth segment.

What I claim is:—

1. The combination of a pair of stationary gongs having internal projections, with framework arranged partly within and partly without the gongs to which the latter are attached, said framework comprising a central ring having arches projecting beyond opposite sides thereof and provided with internal projections at right angles to its main portion for supporting portions of the actuating mechanism.

2. The combination, in a cycle bell, of a spindle having a pair of disks fixed upon it at a distance apart, one of the disks having inclined projections fixed to its flat surface, and also a number of sliding strikers mounted so as to reciprocate thereon, a spur wheel mounted loosely upon said shaft having inclined projections fixed to one of its surfaces, and an annular sleeve having inclined teeth of different sizes and pitch formed respectively on its upper and lower edges adapted to mesh with the inclined projections on the said disk and spur wheel, and means for imparting a rotary motion to the spur wheel and disks.

3. A bell operating mechanism comprising a framework having a bell mounted thereon, a spindle rotatably carried by said framework, a disk fixed on said spindle rotatable therewith, said disk having a number of reciprocating strikers mounted thereon, a spur wheel mounted to turn freely on said spindle, a sleeve adapted to rotate freely on said spindle and to slide longitudinally thereon between the disk and the spur wheel, clutching means on the sleeve to engage said disk and spur wheel, and rotate the disk when the spur wheel is turned in one direction, and free the disk when the spur wheel is rotated in the opposite direction, and means for actuating the spur wheel.

4. A cycle bell comprising a central framework in ring form having a number of internal projections arranged at right angles to its main portion and with an arch projecting beyond each side, a pair of stationary gongs fixed to said arches, provided with internal striking projections, a central spindle mounted in bearings so as to revolve freely between the arches, a pair of disks fixed upon the said spindle at a distance apart, one of said disks being provided with inclined projections in the form of clutch

teeth, a number of sliding strikers mounted loosely upon each disk, a spur pinion mounted loosely on said spindle between the disks and having inclined projections formed on 5 one of its surfaces, an annular ring mounted loosely on said spindle between one of the disks and pinion and provided with inclined teeth on its upper and lower edges of different sizes and pitch adapted to mesh 10 with the inclined projections of the pinion and of the disk, and means for imparting a rotary motion to the pinion and to the disks.

5. The combination in a cycle bell, of frame work having an arch projecting beyond each side, stationary gongs fixed to said arches, and having internal projections, a central spindle rotatable in bearings between the arches, a pair of disks fixed to the spindle, strikers slidably mounted upon 15 each disk and arranged to engage with the internal projections on the gongs, a boss on one of said disks provided with inclined teeth on its face, a spur pinion mounted to turn loosely upon said spindle, a second 20 spindle carried by the frame work, a spur wheel on the second spindle arranged to 25

mesh with the spur pinion on the central spindle, said spur pinion having inclined teeth on one of its faces, a spur pinion on the second spindle, a sleeve mounted to turn 30 loosely and move longitudinally upon the central spindle, said sleeve having teeth of different sizes and pitch on its upper and lower faces adapted to engage respectively with the inclined teeth on the face of the 35 spur pinion, and with the teeth on the face of the boss, and means for imparting motion to the spur pinion on the second spindle for rotating the disks.

6. The combination with a bell, of a rotatable disk having circumferential recesses therein, of flat springs each rigidly secured to said disk at one end, sliding strikers mounted on the free ends of said springs and normally adapted to lie within the recesses in said disk, and means securing said strikers on the free ends of said springs. 40 45
